Inventor,
T. S. Underhill.

UNITED STATES PATENT OFFICE.

T. S. UNDERHILL, OF ST. JOHNSVILLE, NEW YORK.

BEEHIVE.

Specification of Letters Patent No. 26,452, dated December 13, 1859.

To all whom it may concern:

Be it known that I, T. S. UNDERHILL, of St. Johnsville, in the county of Montgomery and State of New York, have invented a new and Improved Beehive; and I do hereby declare that the following is a full, clear, and exact description of the same, reference being had to the annexed drawings, making a part of this specification, in which—

10 Figure 1, is a side view of my invention. Fig. 2 is a side sectional view of ditto, taken in the line $y-y$, Fig. 4. Fig. 3, is a plan or top view of ditto, with the case moved back to expose the combs. Fig. 4, is a horizontal 15 section of ditto, in a closed state taken in the line $x-x$, Fig. 2.

Similar letters of reference indicate corresponding parts in the several figures.

This invention relates to an improvement 20 in that class of bee-hives which are provided with movable frames to support the combs.

The object of the invention is to render the frames more accessible than hitherto and also capable of being manipulated or adjusted with much greater facility, so as to admit of the combs being thoroughly examined and removed if necessary with great celerity.

30 The invention also has for its object the varying of the capacity of the hive to suit the size of the colony, so that the temperature of the former may be kept in a proper even state favorable for the health and comfort of its occupants.

35 The invention further has for its object an economical means for admitting of the adjustment or manipulation of the hive necessary for the examination of its contents and the operating or working therewith.

40 To enable those skilled in the art to fully understand and construct my invention I will proceed to describe it.

A, represents the main portion or body of the hive which may be of quadrilateral form 45 and of the usual or any proper dimensions. This main portion A, may be provided with a spare honey box B, placed on the top of A, and communicating with it by suitable openings a , as shown clearly in Fig. 2. The main portion A, of the hive rests on a base board D, which is provided with a slide b , is perforated and has a wire cloth c , over the perforation to prevent the ingress of millers and other intruders when the slide is withdrawn to admit air—see Fig. 2. Proper 50 openings d , are made in the front of the hive

to permit the bees to pass in and out, and one side e , of the main portion A, of the hive is not permanently attached to it but is allowed to slide in and out of A, and may be secured 55 therein at any desired point by pins f , which pass through holes g , in the front and back sides of A. Within the main portion A of the hive and near one side a series of vertical rods h , are placed as shown in Figs. 3, and 4. 60 These rods h , are attached to pins or plugs i , which are fitted in proper holes in the base board D, and may be readily lifted out at pleasure. On each rod h , a vertical frame E, is hung. These frames are simply wooden 65 bars secured together in quadrilateral form. The rods h , pass through eyes j , attached to one side of the frames, the eyes fitting loosely on the rods. The frames are retained at an equal and suitable distance apart by 70 pins k , at their lower ends, at the sides opposite to those connected to the rods h . The pins k , fit in holes in the upper surface of the base board. The upper part of each frame is provided with a horizontal pin l , which 75 pins serve to keep them in a proper relative position with each other as shown clearly in Fig. 2. The front and back sides of the main portion A, extend down a trifle below the other two sides, and the former are fitted 80 in grooves m , m , made in the upper surface of the base board. The base board D, is fitted by pins n , to a square frame F, which may rest on knobs or short supports o , one at 85 each corner, and to the frame F, and at each side of the base board D, a board is fitted by 90 dowel pins, one board G, being provided with grooves m' , m' , which correspond with the grooves m , m , in the base board. The other board H, has a smooth or plane upper 95 surface.

The bees build their combs within the frames E, the combs of the several frames being separate, that is to say, not connected in any way, the bees having passage ways 100 between the combs. When it is desired to inspect the combs, hooks p , which secure the main portion A, of the hive to the base board, by fitting in staples q , attached thereto, are unhooked, the side e , of the part A, 105 removed and the body moved to one side and over on the board G, as shown in Fig. 3. By this arrangement it will be seen that the interior of the hives is fully exposed and all the frames E, rendered very accessible. The 110 comb of each frame E, may be fully inspected by swinging them out as shown in

Fig. 3, and if necessary each frame can be slipped off from its rod *h*, and moth or other intruders removed. In fact by this invention the hive is placed fully under the control of the owner, and the frames *E*, may be manipulated with such facility that by the aid of any ordinary soother, such as tobacco, the bees will be perfectly tractable and not in the least irritable. In case a colony of bees has more combs than they can occupy or is necessary for them to have the frames *E*, containing the empty combs can be removed and also their rods *h*, and the slide *e*, shoved inward and secured by the pins *f*, so that the remaining filled combs will occupy the whole hive. This is an essential feature of the invention for the hive is kept at a proper temperature in winter by the animal heat of the bees and if the hive is larger than the size of the colony requires, the latter may perish on account of being unable to keep warm. The end pieces *G*, *H*, serve to retain the frames *E*, when they are swung outward, the board *G*, also receiving as previously alluded to the main part *A*, of the hive when shoved off from the frames *E*. The object of having the adjustable boards *G* *H*, is that one

pair will answer for a whole apiary, as the frames *F*, of all the hives may be made precisely similar, and if hives are to be removed for wintering the board *D*, is all that is required to be moved with the hive. The holes *g*, that are not in use may be plugged loosely with pins.

I am aware that movable frames *E*, have been previously used in bee hives and I do not claim such broadly or irrespective of the arrangement herein before described, but,

I do claim as new and desire to secure by Letters Patent,

1. The arrangement of the movable frames *E*, in combination with the sliding hive *A*, and adjustable side *e*, substantially as, and for the purpose set forth.

2. The arrangement of the adjustable boards *G*, *H*, and *D*, placed on a frame *F*, when said parts are constructed as described and used in connection with the sliding hive *A*, for the purpose specified.

T. S. UNDERHILL.
